UNITED STATES PATENT OFFICE.

JOHN OSCAR EMRICH, OF PITTSBURGH, PENNSYLVANIA.

METALLIC DOOR.

1,061,993.

Specification of Letters Patent.

Patented May 20, 1913.

Application filed July 28, 1910. Serial No. 574,408.

To all whom it may concern:

Be it known that I, JOHN OSCAR EMRICH, a citizen of the United States, resident of Pittsburgh, in the county of Allegheny and State of Pennsylvania, have invented a new and useful Improvement in Metallic Doors; and I do hereby declare the following to be a full, clear, and exact description thereof.

10 My invention pertains to improvements in the construction of doors of metallic material, including such doors as are more particularly designated as being of fire-proof construction.

15 The object of my invention is to simplify and improve the manner of combining the parts and to thereby reduce the cost incidental to the construction of such doors.

In the accompanying drawings Figure 1
20 is a view in elevation of a door embodying my invention with the upper panel of glass and the lower panel of steel. Fig. 2 is a side view, in section, of Fig. 1. Fig. 3 is a view on lines III—III of Fig. 1. Fig. 25 4 is a view on line IV—IV of Fig. 1. Figs. 5 and 6 are views on lines V—V and VI—VI respectively. Fig. 7 is a view of a cotter pin. Fig. 8 is a side elevation, in section, wherein both panels are of glass. Fig. 9 is a side elevation, in section, showing a door of all steel construction.

The reference numerals in the following specification refer to like parts in the drawings in which, referring to Fig. 1, a frame 35 composed of the hollow stiles 10, 11, have turned portions 12 adjacent to similarly formed portions 13 on the hollow rails 14, 15, a clamp 16 being adapted to engage the parts 12, 13, as shown in Fig. 6, to combine 40 the stiles and rails. Within the stiles 10, 11, a recess 17 is formed behind each opposite face by the terminal sides 19, 20, thereof, the side 19 having reduced extremities which are inserted in suitable openings in 45 the opposite side 20 and bent to engage the latter as at 22 (Fig. 3) and combine the sides in close relation, the side 20 being extended to form the sash 21 and ending in a loop 20', (Fig. 3). Steel strips 23 are 50 interiorly secured against the outer narrow side of the stile 10 by suitable screws, the adjacent ends of said strips being adapted at 23' to serve as a bearing for a lock, and within the stile 11 a strip 25 having depressions at 25' and bearing points 26 is similarly secured against the inner narrow side

of said stile, which may be cut away at any point opposite the depressions 25' as at 27 (Fig. 1) to permit suitable hinges to be secured within the depressions to the strip 60 25 and flush with the stile. Channels irons 28 are secured by screws 28' to the outer narrow sides of the rails 14, 15, and to the ends of the stiles 10, 11, to close the otherwise open parts of the same (Fig. 1). The 65 rail 14 is preferably formed with oppositely disposed moldings 26' integral with the rail and converging to form a central groove as at 29 along one side of the sash 21 (Fig. 2). The middle rail 30 is formed with a tongue 70 30' at each end thereof, said tongues being inserted within the recess 17 as shown in Fig. 4. When steel, instead of glass, is to be used for a panel, the rails 15 and 30 with moldings 31 and panel 32 are prefer- 75 ably made integral, the space between the panels being filled with mineral wool 32' as shown in Figs. 2 and 5, in which case the construction of rail shown for the sash 21 need not be adhered to. The structure 80 may be strengthened, if desired, by the cotter pins 33 (Fig. 7) inserted through the terminal sides of the stiles and panels 32, the ends of the pins being then turned as shown in Figs. 1 and 5. The upper side 85 of the rail 30 is formed similar to the terminal sides of the stiles, having recesses 34 and reduced portions on the end of one side engaging the opposite side through suitable openings to combine the sides of the rail as 90 shown at 34', (Fig. 2) to form the lower side of the sash 21. A sheet of glass 35 is supported in the sash and surrounding the plane on one side of the sash a molding 36 is secured in position by the loop 36' and 95 tongue 37 engaging the loop 20' and recess 17 (Figs. 3 and 8). Around the opposite plane of the sash the molding 38 is provided with an angular end 38' which is inserted between the glass sheet 35 and the 100 part 19 of the sash, so that the glass 35 is held against lateral movement by the tension of the opposite angular ends 38' (Fig. 3) when the side 37 of the molding is forced into the recess 17. If the lower or 105 additional panels are to be of glass, the construction shown in Figs. 2, 3, 4, will be followed as shown in Fig. 8.

Fig. 9 shows a door constructed entirely of steel, in which the rails and their moldings and also the panels may be integral, the stiles being connected thereto in the

same manner as the other construction, the terminal sides of the stiles, however, instead of being intersectingly connected to combine the same and form a portion of a sash as in Fig. 3, are combined with the steel panels by the cotter pins 33, as shown in Fig. 5, the terminal sides being similarly extended to tensionally sustain the moldings at the ends thereof, as shown in Fig. 5.

10 The separable moldings may be sustained upon the frame of the door entirely by the recessed portion 17 without any other retaining contact with the frame. And bolts may be used instead of cotter pins, as

15 shown, either of which may be used in place of the intersecting of the sides for the purpose of retaining the sides in fixed relation. And it will be obvious that various changes may be made in the construction herein

20 shown and described without departing from the spirit of the invention or sacrificing any of its advantages.

What I claim as my invention is:

1. In a metallic door, stiles having their
25 sides extended in contracted parallel relation toward a plane between the stiles, grooves formed lengthwise in said stiles, unitary panel and rail members in said plane between the stiles, the panel portions
30 of said unitary members engaging the extended parallel parts of the stiles, and the rail parts of said members engaging the grooves of the stiles, and pins engaging said extended parts to combine the same.

2. In a metallic door, stiles having their 35 sides extended in contracted parallel relation toward a plane between the stiles, grooves formed lengthwise in the stiles, unitary panel and rail members in said plane between the stiles, the panel portion 40 of said unitary members fitting slidably between said extended parts and the rail portions of said unitary members fitting slidably into said grooves, pins engaging said extended parts and the panel portions of the 45 unitary members to combine the same, and a molding fitting within said grooves and engaging the ends of said extended parts.

3. In a metallic door, stiles having 50 grooves formed lengthwise on the inner edge of the stile, parts of said stiles being extended in contracted parallel relation to the sides thereof, a unitary rail and panel member in a plane between the stiles, the panel portion of said unitary members fitting slidably between said extended contracted parts, and the rail portion engaging the grooves of the stile, and a sash portion formed on the stiles above said unitary member by the transverse intersection of 55 the extended parts of the stiles.

In testimony whereof, I, the said JOHN OSCAR EMRICH, have hereunto set my hand.

JOHN OSCAR EMRICH.
